United States Patent Office

Des. 194,179
Patented Dec. 4, 1962

194,179

AUTOMOBILE

Wilhelm Hofmeister, Munich, Germany, assignor to Bay-
erische Motoren Werke Aktiengesellschaft, Munich,
Germany

Filed Jan. 25, 1962, Ser. No. 68,514

Term of patent 14 years

Claims priority, application Germany Aug. 1, 1961

(Cl. D14—3)

FIG. 1

FIG. 2

FIGURE 1 is a front elevational view of an automobile showing my new design;

FIGURE 2 is a rear elevational view thereof;

FIGURE 3 is an elevational view of the right side thereof; and

FIGURE 4 is an elevational view of the left side thereof.

The dominant features of my design reside in the portions shown in full lines.

I claim:

The ornamental design for an automobile, substantially as shown and described
